Primary Examiner — Kelley Donnelly(74) *Attorney, Agent, or Firm* — Myers Wolin, LLC(57) **CLAIM**

The ornamental design for a display fixture and pallet, as shown and described.

DESCRIPTION

FIG. 1 is a perspective view of one embodiment of a display fixture and pallet showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof; and,

FIG. 7 is a bottom view thereof.

The broken lines illustrate environment and form no part of the claimed design.
